UNITED STATES PATENT OFFICE.

VERIUS J. METZGER, OF MILTON, PENNSYLVANIA.

COOLER.

No. 916,749.

Specification of Letters Patent. Patented March 30, 1909.

Application filed April 29, 1908. Serial No. 429,902.

To all whom it may concern:

Be it known that I, VERICUS J. METZGER, a citizen of the United States, residing at Milton, in the county of Northumberland and 5 State of Pennsylvania, have invented new and useful Improvements in Coolers, of which the following is a specification.

This invention relates to coolers, the object in view being to provide a practical and inexpensive cooler for water, beer and the like, 10 the construction adapting the liquid to be thoroughly chilled and cooled by merely passing such liquid through the cooler as will hereinafter appear.

With the above general object in view, the invention consists in the novel construction, combination and arrangement of parts as herein fully described, illustrated and claimed.

20 In the accompanying drawings:—Figure 1 is a perspective view of a cooler embodying the present invention, the same being shown partly broken away in section. Fig. 2 is a horizontal section through the same. 25 Fig. 3 is a detail perspective view of the liquid containing element of the cooler.

The cooler contemplated in this invention comprises essentially an ice box 1 which is preferably of the double walled construction 30 illustrated in Figs. 1 and 2. In other words the body of the cooler comprises an outer wall 2 and an inner wall 3 the space between which is packed with any suitable material 35 of low heat and cold conductivity so as to insulate the interior of the box from the outside atmosphere.

The cooler is also provided with a removable lid or cover 5 to give access to the ice compartment thereof, the latter being 40 disconnected at 6.

The liquid containing element of the cooler consists of a plurality of members each comprising an upper tubular head 7, a lower tubular base 8 and a hollow plate or web 9 connecting the cap and base and providing a chilled surface of large area and a water space of narrow confines against which the ice or ice compartment 6 is adapted to bear. By reference to Figs. 2 and 3 it will 50 be observed that two of such water containing members are illustrated and that the same are connected in line with the upper tubular heads 7 by means of an elbow 10 or other tubular connection while the lower

tubular bases 8 are disconnected as shown in Fig. 3 the adjacent ends thereof being sealed by stopper or plugs 11. The outer end of one of the outer tubular bases 8 is left open as shown at 12 to receive an inlet nipple 13 by means of which water is introduced into the water containing element of the cooler. The base section of the other water containing element communicates with a corresponding nipple 14 which passes through the adjacent wall of the cooler and has connected a delivery faucet 15.

16 designates an ice water drain cock for draining off the water from the ice compartment 6. Under the arrangement shown in Figs. 2 and 3, two sides of the ice compartment are occupied by the water containing element of the cooler or in other words, two water containing members are arranged at right angles to each other so as to lie in close proximity to the corresponding inner walls of the ice compartment, the ice bears directly against the tubular heads and bases and also against the hollow plates or webs 9. The water entering one of the tubular bases 8 is carried upward through the hollow plate or wall 9 which spreads the water out into a thin sheet or film, whereby it is more quickly chilled in its passage through the cooler. When the water reaches the tubular head 7 of the first member it is then passed through the connection 10 into the head 7 of the next member, thence downward through the shallow hollow plate or web into the tubular base 8 of the second member and thence outward through the delivery faucet. 90 In this way the water is subjected to a thorough cooling action by contact with the hollow plates or webs of the water containing element, whereby the mere passage of the water through the cooler induces the 95 thorough chilling of the same to a point nearly as low as the temperature of the ice itself.

I claim:—

A cooler comprising an ice box, and a 100 water containing element mounted therein and embodying a plurality of members each comprising a tubular head, a tubular base, and a hollow plate or web connecting the head and base and forming a thin water conducting space between said tubular head and base, the tubular part of one member being placed in direct communication with the cor-

responding tubular part of the succeeding member while the opposite tubular parts are cut off from communication, whereby the water is caused to traverse one of the members in one direction and the succeeding member in the opposite direction, substantially as described.

In testimony whereof I affix my signature in presence of two witnesses.
